UNITED STATES PATENT OFFICE.

FRANK SOLEY, OF PHILADELPHIA, PENNSYLVANIA, ASSIGNOR TO MILLER LOCK COMPANY, OF PHILADELPHIA, PENNSYLVANIA, A CORPORATION OF PENNSYLVANIA.

LOCK.

1,123,200.

Specification of Letters Patent.

Patented Dec. 29, 1914.

Application filed June 9, 1911. Serial No. 632,114.

To all whom it may concern:

Be it known that I, FRANK SOLEY, a citizen of the United States, residing at Philadelphia, county of Philadelphia, and State 5 of Pennsylvania, have invented a new and useful Improvement in Locks, of which the following is a full, clear, and exact description, reference being had to the accompanying drawings, which form a part of this 10 specification.

My invention relates to that class of locks in which the direct controlling means for the bolt is a stump mounted or connected with a stump carrier.

15 The purpose of my invention is to provide such locks of such construction as to require a specific key adapted for each lock and with an arrangement whereby a series of such locks may be controlled by a master 20 key.

Generally speaking, my invention comprises a bolt, a stump and stump carrier, and tumblers, the tumblers having notches adapted to the stump and which when the 25 notches in the tumblers are brought into alinement, allow the movement of the bolt to release the lock.

In my arrangement, the tumblers can be operated by the key to bring first the 30 notches in the tumblers into alinement with the stump and then the further action of the key moves the stump allowing the bolt to be withdrawn. The arrangement may also be such that the stump is moved simultaneously 35 with the tumblers to elevate the stump, the desired extent until it alines with a notch in tumblers which it enters, allowing the bolt to be moved.

I will now describe the embodiment of 40 my invention shown in the drawings, and then specifically point out the invention in the claims.

In the drawings: Figure 1 is a front view of a shackle lock embodying my invention 45 with case opened showing lock in closed position. Fig. 2 is a similar view with lock in open position. Fig. 3 is a section on line 3—3, Fig. 1. Fig. 4^a is a view of regular key for my improved lock. Fig. 4^b is a 50 view of a master key for my improved lock. Fig. 5 is a view similar to Fig. 1. Fig. 6 is a view similar to Fig. 2 of a bolt or latch lock. Fig. 7 is a section on lines 7—7, Fig. 5.

Speaking first of Figs. 1—4, which show 55 a shackle lock. *a* is the shackle, *b* the hold-

ing dog. This dog *b* is held from movement by means of the projection *c* on the bolt *d* against which a projection *e* on the dog *b* rests. The movement of the bolt *d* to release is prevented by means of the stump *f* 60 on the stump carrier *g*. The stump normally strikes the solid portion of the tumblers. In this case the stump and stump carrier are pivoted so as to have only a vertical movement in the arc of a circle. The 65 bolt *d* has a linear movement, being slidable on the guide *w*. The tumblers *h* are pivotally mounted on a stud *j* on the bolt and thereby have both a movement in the arc of a circle and a linear movement. The tumblers have the under-cut portion *i*. The outer surfaces of these tumblers have notches *k* and *o*. The outer surface of the bolt has corresponding notches similarly lettered. The depth of the grooves in the 70 key causes the tumblers to have a proper movement to aline the notches in the tumblers.

The lock may be operated in two ways. A key *l* (see Fig. 4^a) may be provided which 75 need not act upon the stump carrier but may act only upon the tumblers and their coacting bolt. Under the action of this key, the tumblers are moved in the arc of a circle until the notches *k* in the tumblers 80 aline with each other and with the notch *k* in the bolt and with the stump. The cut away portions of the tumblers enable the projection *m* on the key to pass under the tumblers and strike the bolt, moving it laterally when the stump is thus alined with the notches in the tumblers, thereby releasing the dog and the shackle opens. (See Fig. 2). On the other hand, a key *n* may be provided (see Fig. 4^b) having the projecting portion *p* which strikes the stump carrier simultaneously with the action of the key upon the tumblers. This causes a movement of the tumblers in the arc of a 85 circle, arranging a set of notches *o* therein 90 in alinement with each other and with the notch *o* in the bolt. The notches are thus arranged to receive the stump simultaneously 95 with the movement of the stump to aline with said notches. These movements 100 are so timed that the said notches aline and are opposite to the stump at the time the stump is elevated opposite to the notches, 105 and just as the projecting portion *p* of the key *n* strikes the bolt moving it laterally. 110

5 The first mentioned key (see Fig. 4^a) is the regular key for the lock, and each lock may have a different arrangement of notches, thus requiring a different key; that is, the notches *k* may be varied in each lock, there being a corresponding variation in each key. The key *n* (see Fig. 4^b) is the master key, the notches *o* in the tumblers being constant on all the lugs.

10 False shallow notches *q* may be placed on the face of the bolt. Such notches if an effort be made, by hand, to adjust the tumblers to open, will, by the unavoidable movement of the bolt when attempting to open by 15 hand, cause the stump to pass into one of these notches which are insufficient in depth to open the lock, and thus the stump will be held in a locked, although false, position.

20 In order to retract the lock, the movement of the bolt to open is against the action of the spring *r*, and in like manner the movement of the tumblers is against the action of springs *s*. The stump carrier is held normally in its downward position by the 25 action of the spring *t*.

30 The construction shown in Figs. 5, 6 and 7 is quite similar to that of Figs. 1 and 2, except that there is no shackle, and the bolt *d'* is prolonged and forms the actual latch or locking bolt, as shown in Fig. 5. With 35 this exception the construction and mode of operation of the lock of Figs. 5, 6 and 7 is similar to that of Figs. 1 to 3, the same character of tumblers and same character of keys, regular and master key, being used.

Having now fully described my invention, what I claim and desire to protect by Letters Patent is:

40 1. In a lock, in combination, a laterally movable bolt, pivotally and laterally movable tumblers, springs normally holding the

tumblers in their retracted positions, a stump and a pivotally movable stump carrier, a spring normally holding the stump in one position, there being two sets of 45 notches in the outer faces of the tumblers and two corresponding notches in the outer face of the bolt, a key adapted to engage and actuate all the tumblers and move them to bring one set of tumbler notches in alignment with one of the bolt notches and with the stump, and a second key adapted to engage and actuate all the tumblers and the stump and bring the second set of tumbler notches and the stump in alignment with 50 each other and with the other notch in the bolt.

2. In a lock, in combination, a laterally movable bolt; pivotally and laterally movable tumblers, the outer face of the bolt extending beyond the outer faces of the tumblers, springs normally holding the tumblers in their retracted positions, a stump and a pivotally movable stump carrier, relatively deep notches in the outer faces of the tumblers and in the outer face of the bolt; a key adapted to engage and actuate all the tumblers and the stump and thereby align the tumbler and bolt notches with the stump, there being relatively shallow false notches in the outer face of the bolt adapted to engage the stump but of insufficient depth to allow the bolt to move into unlocking position.

3. In testimony of which invention, I have hereunto set my hand, at Philadelphia, on this 5th day of June, 1911.

FRANK SOLEY.
